US00D581620S

(12) **United States Design Patent**
Chu

(10) **Patent No.:** **US D581,620 S**
(45) **Date of Patent:** **** Nov. 25, 2008**

(54) **IRON WITH STEAM GENERATOR**

(75) Inventor: **Francis Wa Chu**, Singapore (SG)

(73) Assignee: **Koninklijke Philips Electronics N.V.**,
Eindhoven (NL)

(**) Term: **14 Years**

(21) Appl. No.: **29/303,275**

(22) Filed: **Feb. 5, 2008**

(30) **Foreign Application Priority Data**

Aug. 21, 2007 (EM) 000776638

(51) **LOC (8) Cl.** **07-05**

(52) **U.S. Cl.** **D32/68; D32/73**

(58) **Field of Classification Search** D32/68,
D32/69-73; 38/15, 77.1-77.9, 79, 96, 106-107,
38/69, 141-142; 248/117.1-117.8; 219/245-259;
392/383

See application file for complete search history.

(57) **CLAIM**

The ornamental design for a iron with steam generator, as shown.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
